UNITED STATES PATENT OFFICE.

DOZIER FINLEY, OF OAKLAND, CALIFORNIA, ASSIGNOR TO THE PARAFFINE COMPANIES, INC., OF SAN FRANCISCO, CALIFORNIA, A CORPORATION OF DELAWARE.

INTERLOCKING SHINGLE.

Application filed November 28, 1921. Serial No. 518,444.

My invention relates to an improvement in roofing materials and particularly to individual overlapping shingle-like units cut from prepared roofing.

5 One of the objects of the invention is the provision of a roofing material having in large degree the beauty and character of the tile roofs of the Latin countries but lighter and less costly than tile.
10 Another object is to the provision of a shingle which may be laid to simulate a tile roof, or in the alternative, may be laid in a geometrical pattern simulating the effect of a slate roof. Thus the dealer in roofing materials having to meet widely varying tastes in his trade, can, with this shingle, fill two demands with the single article.

20 My invention possesses other objects and features of advantage, some of which, with the foregoing, will be set forth in the following description of my invention. It is to be understood that I do not limit myself to the showing made by the said description, as I may adopt variant forms of my invention within the scope of the claims.

Referring to the drawings: Fig. 1 is a plan view of a shingle made in accordance with my invention. For convenience, the 30 principal dimensions of a shingle which I have found highly satisfactory are noted on this figure. Fig. 2 is a plan view of a small portion of roof covered by my shingles laid in geometrical pattern simulating slate. Fig. 3 is a plan view of a small section of roof covered with my shingles laid to simulate tile. Fig. 4 is a plan view of a variant form of my invention. Fig. 5 is a plan view of a portion of roof covered with 40 my shingles laid to simulate irregularly placed tiles so that the effect of an old tile roof is obtained.

One of the objections to the prevailing forms of roofing of the general character to 45 which my shingle belongs is that they give the appearance of flatness, or when the flatness is relieved by various means there is observed a monotony of texture due to the constant repetition of the same geometrical 50 design. Another objection to prevailing designs of types of roofing of this class is that they imitate but one of the natural roofing materials having centuries of use in the building arts, namely slate which they closely copy in flatness of roof texture and me-

ticulous sameness in size and shape of the unit pieces.

While my shingle may be laid in geometrical patterns to simulate slate where such a roof is desired, it is contemplated 60 that the chief application of my shingle will be to produce the effect of a tile roof and this application of the shingle is of chief importance in determining its design.

In terms of broad inclusion my shingle 65 comprises a flat sheet, basically square, but having interlocking keys and notches, and a concave edge which is exposed to the weather when the shingle is laid and which is of prime importance in giving the tile effect. The shingle units are preferably surfaced with finely crushed mineral matter and are laid in overlapping relation from 70 gutter to ridge, each of the rows overlapping the preceding row. Each unit is formed 75 with means whereby it may be interlocked with adjacent units. The units are secured to the underlying roof structure by nails driven thru the superposed portions in each row at points which are covered by the next 80 succeeding row. Because of this overlapping relation there are three thicknesses of material underlying the lower central portion of each unit. This causes a bulging of 85 the superposed units which also materially helps in the suggestion of a tile.

More particularly my invention comprises unit pieces 2 symmetrical in respect of a diagonal line 3. The dimensions shown in Fig. 1 are those of a unit cut from a web 90 or sheet of roofing material 39 inches wide, a convenient width to use in carrying out 95 my invention. Of course I do not limit my invention to the dimensions shown, but the shingles of the dimensions given have been 100 found satisfactory and three such units may be cut across the width of the parent sheet or web with the minimum of waste. The sheets are surfaced with granular matter to simulate the color of slate or tile.

The distance A should be about one half 105 inch less than the distance B, and B should be fully 4½ inches less than the side 4 of the base square as this determines the amount of the overlap at the side of the shingle upon which depends the tightness of the roof. Notches 6 are formed in each of the two adjacent edges 7 of the sheet and near the included corner 8. On each of the 110 corners adjacent the included corner 8 por-

tions 9 are formed, projecting from the edges extending laterally from the notched edges 7. The projecting portions form keys which are adapted to be interlocked with 5 the notches 6 in the corresponding edge of the underlying shingle when the roof is laid, so that the notched edges are in substantial alinement. Between the notches 6 and the key 9 the edge 7 is concave so that when the 10 shingle is laid with this edge exposed the curved lower end of the tile is suggested. The corner of the shingle opposite the concave edges is removed back to a line 11 perpendicular to the diagonal 3 of the basic 15 square. The proportions and configuration of the shingle are dictated by the interlocking character of the units when laid. Because of the symmetry of the shingle, it may be laid with either a right or left lap.

20 In laying a roof, indicated in Fig. 3, shingle 12 is laid in place and a nail 13 driven in. Shingle 14 is then laid with the point 15 of the notch formed by the key 9 in register with the point 17 of the first shingle. 25 Shingle 18 is next laid in the same manner and the row continued to the ridge. A second row is now started with shingle 19, the key 9 of which is interlocked as shown with the lower notch 6 of the shingle 12. The 30 upper corner 20 of shingle 19 overlies the adjacent corner 21 of the diagonally positioned shingle 14, the upper edge 22 underlying the upper edge 23 of the side notch 6. Since the distance A is about one-half inch 35 less than the distance B on each unit it will be noted that the edge 23 of each unit lies about one-half inch down roof from the upper edge (disregarding the key) of the underlying shingle. A nail 24 secures the 40 opposite corner of shingle 19 to the underlying roof structure, and a nail 25 is preferably driven in each unit closely adjacent to corner 17 where there are but two thicknesses of material. This nail serves to draw 45 down the part at this point so as to emphasize the central bulge. Shingle 26 is next applied overlying the side of shingle 14 and the upper part of shingle 19, the key 9 being interlocked with the lower notch 6 of shingle 50 14. A nail 27 is then driven thru the overlapping thicknesses of shingle 26 and shingle 19. The third shingle in the second row is then applied in the same manner its key interlocking with the lower notch 6 of shingle 55 18, and its upper edge interlocking in the side notch 6. Additional rows are then applied in the same manner until the surface of the roof is covered. Gutter, ridge and hip edges are also covered, the shingles 60 being cut as required to form the necessary edges or contacts in a manner known to roofers. It will be observed that under the lower middle portion of each shingle as for instance shingle 26 there are three thicknesses of material, namely, portions of shin-

gles 12, 19, and 14. This has the effect of raising the center of the shingle and is of material value in carrying out the illusion of a tile.

In the roofing thus made there is therefore 70 exposed a series of overlapping pieces with curved edges presented on the downward part, the central portions of these pieces being raised above the other portions because of the underlying thicknesses of the roofing 75 material. The illusion caused by raising the central portions of the pieces may of course be increased by laying thin partly rounded strips of wood on the underlying 80 roof structure and properly spaced to come on the median line of each row of shingles. Generally speaking however this is not necessary the curve of the edge and the rise in the center being sufficient to give to the roof an appearance very like that of tile. 85

The laying of my shingles in a geometrical pattern, like that illustrated in Fig. 2, needs little explanation as such manner of laying is common in the roofing arts. The spacing for laying in such manner is determined by 90 making the distance B (Fig. 1) a gauge for the normal distance between the two pairs of diagonally positioned sides of the geometrical figure outlined by the shingles. 95

In Fig. 5 an irregular laying of the shingles is illustrated. This is effected by taking advantage of play in the interlock as well as by forcing the flexible material slightly. Shingles 30 with portions cut away 100 are slipped into place at intervals to give the effect of tile which has become displaced as in old roofs. In Fig. 4 I have shown a modified form of my shingle formed on the same base square and having a concave edge 31, key 32, and notch 33, similar to those already 105 described in connection with Fig. 1, formed in one side only of the piece. On the adjacent side a tab 34 is formed which is adapted to be folded back upon the body of the sheet. In laying this shingle, the procedure is the 110 same as that previously described. The distance from the upper end of the tab to the upper edge of the sheet is made equal to the distance which the edge 36 extends down roof from the upper edge of the underlying shingle. 115

In laying the shingle shown in Fig. 4 procedure is much the same as that previously described. The key 32 is interlocked with the notch 33 of the adjacent shingle and the corner 38 slipped under the edge 36 of the shingle diagonally disposed above and to the left. Nails are driven as before described and the tab 34 folded over 120 and nails 39 driven thru the fold. The fold materially assists in making the side lap of the shingle tight against weather. It also causes the center of the shingle to assume 125 a curve or arch which aids in the illusion desired. As this shingle can be used in but 130

one position when laid to simulate tile, that is with its curved edge downward, it becomes possible to color the parent sheet, from which the shingle is cut, in such manner that the center line of the shingle has a lighter shade of mineral than the edges. This produces in the laid shingle the impression of high light which also contributes to the illusion of tile which is sought. The shingle is cut with the axis of the simulated tile parallel to the long axis of the parent sheet of roofing material and it is therefore easy to sprinkle mineral granules of different shades in zones on the sheet which zones are at predetermined places with regard to the position of the edges and center line of shingles subsequently cut from the parent sheet.

This shingle may also be laid in the manner shown in Fig. 2, the tab however not being folded over. If there is a shading of granular matter on the shingle to produce an art effect when laid tile fashion such shading is broken up and tends to eliminate the dead flatness of the geometric pattern of roof.

I claim:

1. A shingle comprising a sheet of roofing material having a straight edge and a concave edge adjacent thereto, said shingle formed with interlocking means disposed at opposite ends of said concave edge for interlocking adjacent shingles when the concave edges of adjacent shingles present a substantially continuous edge to the weather.

2. A shingle comprising a basically square sheet of roofing material having a notch on one edge near one corner of the sheet and having the opposite corner removed along a line substantially parallel to a diagonal of the sheet intercepting the intermediate corners, and a key formed on one of the intermediate corners.

3. A shingle comprising a sheet of roofing material having a concave edge for exposure to the weather and a notch in said concave edge near one corner of the sheet, and a key portion on the adjacent corner of the concave edge adapted to interlock with the notch of the underlying shingle when the roof is laid.

4. A shingle comprising a sheet of roofing material having a notch on one edge near one corner of the sheet, and a key portion on the adjacent corner adapted to interlock with the notch of the underlying shingle when the roof is laid, that portion of the edge between the key and the notch being concave.

5. A shingle comprising a basically square sheet of roofing material having a concave edge and one of the corners opposite to said edge removed along a line substantially perpendicular to the diagonal of the sheet.

6. A shingle comprising a sheet of roofing

material having a notch on each of two adjacent edges near the included corner, and a key portion on each of the corners adjacent said included corner, either of said key portions being adapted to interlock with the notch in the corresponding edge of the underlying shingle when the roof is laid.

7. The combination of shingle units comprising overlapping rows of overlapping units, the rows extending from gutter to ridge and each unit overlapping the next lower unit, each unit comprising a basically square sheet of roofing material having a key at one corner and notches in the two sides bounding one of the adjacent corners, and having the other adjacent corner removed to form an oblique edge substantially parallel to a diagonal of the sheet intercepting the key corner whereby in each unit, the key is interlocked with one of the notches of the nearest adjacent unit at the side, and the oblique edge is interlocked with the other notch of the diagonally positioned unit above.

8. The combination of shingle units comprising overlapping rows of overlapping units, the rows extending from gutter to ridge and each unit overlapping the next lower unit, each unit being formed with a notch and a key whereby the key of each unit is interlocked with the notch of the nearest adjacent unit at the side, one of the upper corners of each unit overlying the adjacent corner of the diagonally positioned unit above.

9. A shingle comprising a sheet of roofing material having a notch in the edge exposed to the weather when laid, and a key portion on an adjacent lateral edge adapted to interlock with the notch of the underlying shingle when the roof is laid whereby adjacent shingles present a substantially continuous lower edge to the weather.

10. A shingle comprising a flat sheet of roofing material having a concave edge and a straight edge adjacent said concave edge for optional exposure to the weather when laying.

11. A shingle comprising a basically square sheet of roofing material having a key at one corner and notches in the two sides bounding one of the adjacent corners and having the other adjacent corner removed to form an oblique edge substantially parallel to a diagonal of the sheet intercepting the key corner.

12. A shingle comprising a basically square sheet of roofing material having a key on each of two corners on a diagonal and a notch in each side near one of the adjacent corners, the other adjacent corner being removed to form an oblique edge substantially parallel to said diagonal.

In testimony whereof, I have hereunto set my hand.

DOZIER FINLEY.
